CLAIM

I claim the ornamental design for a RC car, as shown and described.

DESCRIPTION

FIG. 1 is a front perspective view of a RC car.

FIG. 2 is a rear perspective view of the RC car of FIG. 1.

FIG. 3 is a side view of the right side of the RC car of FIG. 1.

FIG. 4 is a side view of the left side of the RC car of FIG. 1.

FIG. 5 is a front view of the RC car of FIG. 1.

FIG. 6 is a rear view of the RC car of FIG. 1.

FIG. 7 is a top view of the RC car of FIG. 1; and,

FIG. 8 is a bottom view of the RC car of FIG. 1.

The broken lines shown are included for the purpose of illustrating the unclaimed portions of the article and forms no part of the claimed design.
